UNITED STATES PATENT OFFICE.

MARSEILLES McEWEN WILKINSON, OF MEMPHIS, TENNESSEE.

DETACHABLE BATTERY LAMP.

Application filed November 21, 1925. Serial No. 70,518.

This invention relates to improvements in detachable battery service lamps, commonly called trouble lights. An object of this invention is to provide a low voltage trouble or working lamp that may be used in taking batteries from automobiles at night, or for other appropriate purposes.

Another object is to provide a trouble lamp that may be used with practically any defective battery. It very seldom happens that a defective battery will not have at least, one cell that will give a three ampere light.

A further object of this invention is to provide flexible connections to the trouble light thereby making it possible to bend the light to any direction desired, the connection being constructed to give the needed flexible qualities, at the same time assuring sufficient rigidity for properly supporting the light. Other objects will appear in the following detailed description, and in the single sheet of drawings, herewith made a part of this application:

25 In the drawings,

Fig. 1 illustrates a side elevational view of the trouble lamp and connections in assembled form.

Fig. 2 represents a sectional side elevation-
30 al view of the trouble lamp, showing the lamp and circuit connections thereto in proper assembled relationship to each other.

Fig. 3 illustrates in perspective the different elements of the circuit connections, arranged in series previous to placing them together in assembled form.

Numeral 1 designates a detachable battery service light, or more commonly called trouble light, having flexible circuit connections 2 and 3 leading therefrom, the free ends of the connections 2 and 3 being supplied with terminal clips 4 and 5. In order to provide sufficient rigidity for supporting the light in a desired position, at least one of the flexible circuit connections as, for instance 3, is supplied with an outer covering comprising metal strips 6 wound spirally over the usual insulating material 7 of

the ordinary flexible connection. The flexible circuit connections 2 and 3 are placed in 50 circuit with the lamp preferably by means of the arrangement disclosed in Figures 2 and 3, as by means of the outer sleeve portion 8, the inner sleeve portion 9, the circular contact element 10 and the lamp connection 11 into which the lamp 1 and the lamp shade 12 is adapted to be removably attached. The circuit terminal elements 8, 9, 10 and 11 may be of any suitable material. The terminal spring clips 4 and 5 are readily adapted for connection with the terminal elements of a storage battery. In this invention a low voltage trouble light is provided, preferably a 2 volt light, it being understood that almost any defective battery 65 will have at least one cell that will give a three ampere light, wherein other devices now in common use call for a 6 volt light, which obviously, makes it impossible to supply a means of light from the ordinary defective battery. This invention provides a light and connections which can be easily and quickly attached across a center cell of the battery. The flexible connections having at least one connection of comparative 70 rigidity making it possible to maintain the trouble light in a reasonable set position when desired. This invention is particularly adapted for tourists' use, and may be utilized by all service cars.

What I claim is:

In a trouble lamp, flexible connections extending therefrom, enclosing means for providing rigidity to the flexible connections, means for bringing the flexible connections into circuit with a lamp consisting of an outer sleeve portion, an inner sleeve portion, a contact element, having a circular clamping portion integral therewith, a lamp connection for receiving the 90 clamping element, terminal spring clips at the free ends of the flexible connections for the purpose of connecting with the ordinary terminal elements of a storage battery.

In testimony whereof I affix my signature.

MARSEILLES McEWEN WILKINSON.
